This invention relates to the advertising of goods and to the like. It is particularly concerned with a device for holding price tickets and advertising matter which may be applied to containers such as cans or bottles.

UNITED STATES PATENT OFFICE

2,263,235

TICKET HOLDER AND ADVERTISING DEVICE

Morris Cooper, Chicago, Ill.

Application February 25, 1939, Serial No. 258,433

2 Claims. (Cl. 40—11)

This invention pertains to ticket or card holders particularly adapted for holding price tickets and mounting or applying them to containers such as cans or bottles.

Another feature of the invention consists in the provision of means for showing or applying advertising matter such as the name of a manufacturer, to the holder so that it will be displayed whenever the holder is used.

The objects of this invention are to provide a simple and efficient device for the purposes set forth which may be made at a low cost whereby it will be adapted for use as a premium article; to provide a device of the character set forth which may be readily attached to and detached from containers; and to provide such other improvements in construction and advantages in use as will appear from the following description.

In the accompanying drawing illustrating this invention,

Figure 1 is a front view of the holder indicating the same as applied to a can shown in dotted lines and also showing a price card in dotted lines;

Figure 2 is a side view of the same with the holder shown adjusted to different positions;

Figure 3 is a front view showing a modified form;

Figure 4 is a front view showing a further modification;

Figure 5 is a rear view of the device shown in Figure 4;

Figure 6 is a side view of the same; and

Figure 7 is a plan view of the form shown in Figure 4.

As shown in Figures 1 and 2 the holder comprises a clamp or band 10 which is shaped to conform to or be attached to an article such as a can indicated at 11. The clamp or fastening member 10 is preferably made of resilient metal and is somewhat more than a semi-circle with the ends 12 turned outwardly so that it may be readily slipped over a can and will hold securely in position. A stem 13 preferably formed of easily bendable metal is fastened to the flat strip at 14 as by spot-welding and supports the card holder 15 which is preferably formed of wire bent to the form shown and spot-welded or otherwise secured at 16 to the stem.

While the card receiving member 15 may be made in various forms it is preferably made as shown, having the general configuration of the letter M with the ends extending upwardly and forming loops for receiving a card 17. A plate 18 for receiving advertising matter is secured to the center and loop portions of the card receiving

member 15 and may have a manufacturer's name or the like applied directly thereto or it may be made as shown in channel form for receiving a card as indicated at 19 which may be clamped securely therein by compressing the edges of the plate.

When the device is to be used the clamp or band 10 is pressed over a can and the stem 13 will usually be arranged to extend up and forwardly to prominently display the price card or it may be bent to the position shown in dotted lines in Figure 2 or in any other desired position within the range of its adjustment or bendability.

For this purpose, the stem 13, as shown in Figs. 1 and 2, is preferably made sufficiently long so that the card holder may be bent or twisted in order to present the card in a large variety of positions with respect to the can, bottle, or other article to which it is applied. For instance, the stem may be twisted to present the card holder at substantially 90 degrees to the position shown in Figs. 1 and 2 or so that it would be in view at the side of the can instead of in front of it. The stem may also be bent to show the card above or at the back of the can or at any other position desired within the range of the stem and associated parts.

In the modification shown in Figure 3 the card receiving member 20 is secured directly to a clamp or band 21 and any adjustability is dependent upon bending of the wire branches of said member.

The form shown in the remaining figures comprises a clamp or band 22 which is shaped for engagement with the neck of a bottle with a plate or channel 23 secured directly thereto as by spot-welding. The card receiving element 24 is in turn spot-welded or otherwise fastened directly to the plate 23 as shown. The use or operation of this form will be evident to those familiar with such devices.

While I have shown preferred forms of my invention as embodied in devices in commercial use, it is apparent that changes may be made in the form or arrangement of the parts in order to adapt the same to different containers, different cards, or the like, and therefore I do not wish to be limited to the particular form shown except as specified in the following claims, in which I claim:

1. A combined ticket holder and advertising device comprising a band of resilient material adapted to clamp on a container, a stem formed of readily bendable metal having one end secured

to the band, a card receiving element fastened to the opposite end of the stem, and a plate on said element for receiving advertising matter or the like, the arrangement being such that the card receiving element and plate may be presented at a large variety of positions with respect to the container.

2. A combined ticket holder and advertising device comprising a clamp member adapted to be detachably engaged with a container or the like, a long pliant, bendable stem having one end secured to the clamp member, a ticket holder se-

cured to the opposite end of the stem, and a plate for advertising matter attached directly to the ticket holder in advance of the point of attachment of the stem to the ticket holder, the construction being such that the stem may be twisted or bent at any point between the clamp member and the ticket holder in order to present the ticket holder at different angles and positions with respect to the container or the like to which the clamp is attached.

MORRIS COOPER.
